(57) **CLAIM**

The ornamental design for an air fryer, as shown and described.

DESCRIPTION

FIG. 1 is a top, front, left perspective view of an air fryer showing my new design therefor;
FIG. 2 is a front elevation view thereof;
FIG. 3 is a rear elevational view thereof;
FIG. 4 is a right side elevational view thereof, with the left view being identical;
FIG. 5 is a top plan view thereof;
FIG. 6 is a bottom plan view thereof; and
FIG. 7 is a view similar to FIG. 1 showing the air fryer with its handle in a different position;
FIG. 8 is a front elevational view of the position shown in FIG. 7;
FIG. 9 is a rear elevational view of the position shown in FIG. 7;
FIG. 10 is a side elevational view of the position shown in FIG. 7, the opposite side being identical;
FIG. 11 is a top plan view of the position shown in FIG. 7;
FIG. 12 is a bottom plan view of the position shown in FIG. 7;
FIG. 13 is a top, front, left perspective of the upper part of an air fryer for separate protection independent of the bottom part;
FIG. 14 is a front elevational view of the design shown in FIG. 13;
FIG. 15 is a rear elevational view of the design shown in FIG. 13;
FIG. 16 is a side elevational view of the design shown in FIG. 13;
FIG. 17 is a top plan view of the design shown in FIG. 13;
FIG. 18 is a bottom plan view of the design shown in FIG. 13;
FIG. 19 is a top, front, left perspective view of the bottom portion of an air fryer showing my new design therefore for independent protection;
FIG. 20 is a front, elevational view of the design shown in FIG. 19, the rear view being identical;
FIG. 21 is a side elevational view of the design shown in FIG. 19, the opposite side being identical;
FIG. 22 is a top plan view of the design shown in FIG. 19; and,
FIG. 23 is a bottom plan view of the design shown in FIG. 19. Through out the drawings the broken lines depict environment and form no part of the design.
